(57) **CLAIM**

The ornamental design for a vehicle trim package, as shown and described.

DESCRIPTION

FIG. 1 is a front perspective view of a vehicle trim package according to a first embodiment of our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof; and

FIG. 7 is a top view thereof.

FIG. 8 is a front perspective view of a vehicle trim package according to a second embodiment of our new design;

FIG. 9 is a rear perspective view thereof;

FIG. 10 is a front view thereof;

FIG. 11 is a rear view thereof;

FIG. 12 is a right side view thereof;

FIG. 13 is a left side view thereof; and,

FIG. 14 is a top view thereof.

The broken lines showing a vehicle are provided for the purposes of illustrating environmental structure that forms no part of the claimed design.

1 Claim, 12 Drawing Sheets
